UNITED STATES PATENT OFFICE.

GEORGE W. GOMBER, OF CONYNGHAM, PENNSYLVANIA, ASSIGNOR TO STANDARD AUTOMATIC MACHINE COMPANY, OF PITTSBURGH, PENNSYLVANIA, A CORPORATION OF DELAWARE.

COIN-CONTROLLED MECHANISM FOR VENDING-MACHINES.

1,293,084.

Specification of Letters Patent.

Patented Feb. 4, 1919.

Application filed November 9, 1917. Serial No. 201,128.

To all whom it may concern:

Be it known that I, GEORGE W. GOMBER, a citizen of the United States, residing at Conyngham, in the county of Luzerne and 5 State of Pennsylvania, have invented a new and useful Coin-Controlled Mechanism for Vending-Machines, of which the following is a specification.

This invention has reference to coin-controlled mechanism for vending machines, and its object is to provide a mechanism which may be readily set to cause the delivery of a single article on the deposition in 10 the machine of a suitable coin, or the delivery of a chosen number of articles on the deposition in the machine of another coin of higher denomination, the arrangement being such that the actuating mechanism may, in most part, be the same for delivering a single article or a multiple thereof.

The invention is designed primarily for use in connection with cigar vending machines where it is customary to sell six 5 cent cigars for twenty-five cents or three 10 cent 25 cigars for twenty-five cents or some other such arrangement.

The vending machine embodying the invention is provided with a slide structure having an accessible end by which it may 30 be manipulated. The slide structure is arranged for connection to the vending or delivery side of the machine which may be of appropriate structure but which does not enter into the present invention. A vending or delivery mechanism well adapted for 35 use in connection with the coin-controlled mechanism of the present invention is shown and described in another application for vending mechanism, Serial No. 201,129, filed 40 by me on even date herewith.

There is also provided latch mechanism responsive to inserted coins, and this latch mechanism which is primarily of single stroke type has associated therewith a device by which the latch mechanism is held out of active position during a predetermined number of reciprocations of the push bar to ultimately release the latch mechanism to its first position.

50 By the provision of two machines, one of which is set for single stroke operation and the other of which is set for multiple stroke operation, it is possible to vend a single cigar for five cents or six cigars for twenty-

five cents, as the case may be, or any other 55 chosen relation of vending.

The invention will be best understood from a consideration of the following detailed description, taken in connection with the accompanying drawings forming part 60 of this specification, with the further understanding that, while the drawings show a practical form of the invention, the latter is not confined to any strict conformity with the showing of the drawings but may be 65 changed and modified so long as such changes and modifications come within the scope of the appended claims.

In the drawings:

Figure 1 is a side elevation of a coin-controlled mechanism embodying the invention and showing the twenty-five cent side thereof;

Fig. 2 is a plan view of the structure of Fig. 1, with some parts in cross section;

Fig. 3 is a view similar to Fig. 1, but viewing the other face thereof and showing the five cent side;

Fig. 4 is a longitudinal upright section taken back of the face plate shown in Fig. 1, 80 and also omitting some of the parts;

Fig. 5 is a section on the line 5—5 of Fig. 4;

Fig. 6 is a view similar to Fig. 1, but with the push bar at the other extremity of 85 its stroke and showing the parts in position for vending numerous articles for one coin;

Fig. 7 is a perspective view of a main portion of the push bar;

Fig. 8 is a perspective view of a portion of 90 the latch mechanism.

Referring to the drawings, there is shown a casing 1 in which the coin-controlled mechanism is housed and which may be of any suitable configuration.

The coin-controlled mechanism includes an intermediate plate 2 and flanking plates 3 and 4 respectively secured to the plate 2 in any suitable manner and spaced therefrom by spacing strips 5 or by any other means 100 answering the purposes of the invention.

Extending lengthwise of the plate 2 between the latter and the plate 3 is a push bar 6 projecting through the casing and provided with a manipulating head or knob 7. 105

The push bar 6 is in the form of an elongated strip having a recess 9 in one edge, which is the upper edge in the installed

position, such recess being of an extent lengthwise of the bar about equal to or a little greater than the diameter of a chosen coin, say, a quarter-dollar. On the other 5 side of the plate 2 remote from the push bar 6 is a supplementary push bar 10 also provided with a notch or recess 11 similar to the recess 9. The recesses 9 and 11 may be of the same size, or the recess 11 may more 10 nearly correspond in extent to the diameter of a five-cent piece. The bottom edge of each notch or recess is beveled as indicated at 12, with the bevel directed outwardly.

In each plate 3 and 4, there are openings 15 13 and 14 respectively, into coincidence with either of which the recess or opening 9 or 11 may be brought. The bottom edges of the openings 13 and 14 are beveled as indicated at 15.

20 Leading from the exterior of the casing 1 to a position to discharge over the openings 13 is a double coin chute 16, that is, it is provided with two channels 17 and 18 respectively, these channels being accessible 25 from the exterior of the casing and may have mouth portions or cover plates of customary character, of such size as to admit a designated coin but no others. For instance, the coin chute channel 17 discharging opposite the opening 13 of the plate 3 30 may be arranged to transmit quarter-dollars, while the other channel of the coin chute may be arranged to transmit five-cent pieces or nickels.

35 The arrangement shown in the drawings with respect to the coin chutes is of the simplest kind, but it will be understood that if so desired, various devices for preventing the use of any but proper coins may be 40 employed.

When a coin is lodged at the opening 13, it is in position to drop into the recess 9 when the push bar is suitably locked with respect thereto, and when the coin is in the 45 recess 9, it is drawn by the push bar toward the opening 14, which latter is large enough to permit the coin to escape, such escape being facilitated by the beveled edges 12 and 15. If the coin be too small, it will 50 escape through the opening 13, being facilitated in such escape by the beveled edges 12 and 15 of the recess 9 and the opening 13. In this manner, a coin such as a ten-cent 55 piece or a cent will fail to operate the machine, because it will not remain in the recess 9 of the bar 6 while the latter is being manipulated to operate the vending side of the machine.

The bar 6 along one edge is provided with 60 a series of teeth 16^a and also with a notch 17^a. The teeth 16^a are engaged by a double tooth rock pawl 18^a pivotally mounted by a screw 19 or otherwise on the plate 2 and controlled by a spring 20 so as to yield to 65 the passage of the teeth 16 but be held in

engagement with some one of them. A finger 21 is carried by the bar 6 so as to engage one or the other of the teeth of the pawl 18^a and cause it to rock.

The teeth 16^a and pawl 18^a constitute a 70 full stroke device necessitating the movement of the push bar 6 to its full extent and preventing partial movement thereof. This feature, however, does not enter particularly into the present invention, and is furthermore of known construction, wherefore further description is deemed unnecessary.

Also mounted on the push bar 6 so as to move therewith is a pawl 22 with a nose end 23 and a weighted end 24, the latter being heavy enough to overbalance the nose end and normally rest upon a stop bracket 25 carried by the push bar. In the path of the nose end 23 of the pawl 22 is a circular series of pins 26 mounted on a disk 27 between the plate 3 and a bracket 28, the disk being rotatable about its axis with the bracket 28 bearing with some frictional pressure upon the disk, which latter is provided with a pintle 29 to support it. The pins 26 are all of the same length except one pin 26^a, which is longer than the other pins, but all the pins are so disposed with relation to the pawl 22 as to be engaged thereby for turning the disk step by step by the 95 reciprocal movement of the bar 6 participated in by the pawl 22 carried by the bar.

Mounted on the plate 3 is a rock member 29 having three arms 30, 31 and 32 respectively. One arm 30 has a normal position nearly upright, and is formed on one side with a shoulder 33 for a purpose to be described. The arm 32 is counterweighted to overbalance the rest of the device 29, and the arm 31 is bent to one side to be out of the path of the pins 26 but in the path of the pin 26^a.

Mounted between the plates 2, 3 and 4 is a cam block 34 having cam members 35, 36 extending into the spaces between the plates 2, 3 and 4 so as to be in the path of coins inserted in the machine. The cam block 34 carries one end of an arm 37 projecting toward that end of the push bar 6 containing the notch 17^a, and at such point the arm 37 carries a tooth 38 in position to enter the notch 17^a. The arm 37 is also provided with spaced pins 39 and 40, the pin 39 acting as a stop pin for the arm 30, and the pin 40 being positioned to engage the shoulder 33 under circumstances to be described. A normal tendency to move in one direction is imparted to the push bar 6 by a spring 41.

When the machine is installed, the mouth of one or the other of the coin chutes 17 and 18 is closed, so that only one of the coin chutes is exposed, and this is the one leading to the part of the apparatus which will 130

permit the vending of the desired number of cigars for one coin. Let it be assumed that the machine is set to vend a single cigar for a single coin, such as a five-cent piece. 5 Under these circumstances, the coin chute 17 is closed and the coin chute 18 is left open, the latter leading to the part of the machine responsive to a five-cent piece. On the insertion of such coin, it drops to the bar 10 6, which latter is in the retracted position on account of the normal action of the spring 41. The recess 11 of the supplementary bar 10 belonging to the bar 6 is at the time beneath the coin chute, wherefore the 15 deposited coin drops into the recess 11 and there lodges. Now, on pulling out the bar 6, which has a limited lost motion, the deposited coin engages the proper side of the cam block 34, causing the cam block with its arm 20 37 to rise a short distance. This distance is sufficient to carry the tooth 38 out of the notch 17^a and thereby permit the full stroke of the bar 6, which full stroke would otherwise be prevented by the engagement of the 25 tooth 38 in the notch 17^a. The desired forward stroke of the bar 6 may then be accomplished and the cigar or other article be vended.

If it be that the machine is set for vending several articles in succession for a single coin, then the device is initially set to permit the insertion of a coin such as a quarter in the coin chute 17. Under these circumstances, the larger coin, on engaging the 30 proper portion of the cam block 34, say, the cam portion 35, raises the cam block to a greater extent, thus lifting the arm 37 until it is higher than the shoulder 33, whereupon the counterweight 32 causes the arm 30 to 35 move so that the pin 40 will rest upon the shoulder 33, thus holding the arm 37 and cam block 34 in the elevated position. There is now no impediment to the repeated reciprocation of the bar 6 which may be continued until ultimately the elongated pin 40 40 is brought into engagement with the arm 31, causing a rocking of the arm 30 to carry the shoulder 33 out of the path of the pin 40, whereupon the weight of the arm 37 causes the latter to drop and the finger 38 45 once more sets in the notch 17^a and further reciprocation of the bar 6 is prevented.

The number of times the bar 6 may be reciprocated depends upon the number of 50 pins 26, so that the machine may be built to vend either one cigar for five cents, or six cigars for twenty-five cents, or one cigar for ten cents and three cigars for twenty-five cents, or six cigars for fifty cents, or 55 any other amount desirable.

To surely discharge the inserted coins after causing the release of the coin lock, the plate 2 opposite the openings 13 and 14 has cam lugs 42 with one of which lugs an inserted coin engages and is positively ejected 60

through the opening 13 or 14 as the case may be.

What is claimed is:

1. In a coin controlled mechanism for vending machines, an elongated reciprocatory push bar having a coin receptacle formed therein, a latch member pivoted to a fixed part of the machine and provided at one end with means for engaging the push bar and at the other end with means 70 in the path of a coin lodged in the coin receptacle of the push bar to rock the latch member out of engagement with the push bar, means for temporarily holding the push bar engaging end of the latch member in 75 the inactive position, and step by step means under the control of the push bar and collectively related to the holding means of the latch member to release the latter after a predetermined number of reciprocations 80 of the push bar.

2. In a coin controlled mechanism for vending machines, an elongated reciprocatory push bar having a coin receptacle formed therein, an elongated latch member overriding the push bar and pivotally mounted on the fixed part of the machine, said latch member having engaging means for the push bar at one end and cam means at the other end in position to be engaged by 95 a coin deposited in the coin receptacle of the push bar, means for temporarily holding the latch member in the inactive position, and step by step means responsive to reciprocations of the push bar and movable to engage the holding means for the latch member to release the latter after a predetermined number of reciprocations of the 100 push bar.

3. In a coin controlled mechanism for vending machines, an elongated push bar having a coin receptacle formed therein and also provided with a notch, a latch lever pivoted to a fixed part of the machine and extending in the direction of reciprocation 105 of the push bar along the latter, said lever being provided at one end with a tooth for engaging the notch in the push bar and at the other end with a cam block in overriding relation to the coin receptacle in the 110 push bar for engagement with the cam of a coin deposited in the coin receptacle, a rotatable series of pins with one pin longer than the others, a pawl carried by the push bar and movable into engagement with the pins 115 120 one at a time on the reciprocation of the push bar, and a rock lever mounted on a fixed portion of the machine with one arm in position to be engaged by the elongated pin and the other arm in position to engage and hold the latch lever in position to release 125 the push bar for reciprocation.

4. In a coin controlled mechanism for vending machines, a reciprocatory push bar having a receptacle for an inserted coin, a 130

latch member mounted on a fixed part of the machine, said latch member having a portion to directly engage and hold the push bar from reciprocation and another portion in the path of a coin lodged in the coin receptacle of the push bar to release the latter, means for holding the latch member temporarily in the inactive position, and means for causing the release of the latch member to move to active position after a predetermined number of reciprocations of the push bar.

5. In a coin controlled mechanism for vending machines, a reciprocatory push bar formed with a coin receptacle and with a notch, a latch lever mounted to rock on a fixed axis in operative relation to the push bar, said lever having a tooth for engaging the notch in the push bar to hold the latter against reciprocation, and a cam in position to be engaged by a coin deposited in the coin receptacle of the push bar, a rotatable series of pins on the machine with one pin longer than the others, means on the push bar for engaging the pins in succession to rotate the series of pins, and a rock lever mounted on a fixed portion of the machine, said lever having an arm in the path of the longer pin and another arm in position to hold the latch end of the latch lever in the inactive position.

6. In a coin controlled mechanism for vending machines, a reciprocatory push bar formed with a coin receptacle and with a notch, a latch lever mounted to rock on a fixed axis in operative relation to the push bar, said lever having a tooth for engaging the notch in the push bar to hold the latter against reciprocation, and a cam in position to be engaged by a coin deposited in the coin receptacle of the push bar, a rotatable series of pins on the machine with one pin longer than the others, means on the push bar for engaging the pins in succession to rotate the series of pins, and a rock lever mounted on a fixed portion of the machine, said lever having an arm in the path of the longer pin and another arm in position to hold the latch end of the latch lever in the inactive position, the rock lever having a shouldered portion and the latch lever having a pin for engaging the shouldered portion to hold the latch lever in the inactive position.

7. In a coin controlled mechanism for vending machines, a reciprocatory push bar having a coin receptacle therein, a pivoted

latch bar associated with the push bar, said latch bar having a cam at one end and a tooth at the other end for engaging and locking the push bar against movement in one direction, with the cam in position to be engaged by a coin lodged in the coin receptacle of the push bar, a rock lever having a shouldered portion in position to engage and hold the latch bar out of operative relation to the push bar, a pawl on the push bar, and a freely rotatable member, with a circular series of parts in the path of the pawl and with one of said parts in position to engage the rock lever, whereby a predetermined number of reciprocations of the push bar will cause the release of the latch bar for engaging and stopping the push bar.

8. In a coin controlled mechanism for vending machines, a push bar having a plurality of receptacles for coins of different sizes, a latch bar for the push bar provided with cam portions in the paths of coins lodged in the coin receptacles for causing the release of the push bar by a coin, means for temporarily holding the latch bar out of engagement with the push bar, and means under the control of the push bar for causing the actuation of the holding means for the latch bar to release the latter after a predetermined number of reciprocations of the push bar.

9. In a coin controlled mechanism for vending machines, a reciprocatory push bar having a plurality of adjacent coin receptacles, a single latch bar for the push bar pivoted to a fixed part of the machine and provided with means in the paths of inserted coins to be moved out of latching engagement with the push bar by one or the other of the coins, holding means for the latch bar for engaging it when moved to released position by one of the coins, and a freely rotatable member under the control of the push bar and provided with means for engaging the holding means for the latch bar and releasing the latter from said holding means after a predetermined number of reciprocations of the push bar.

In testimony, that I claim the foregoing as my own, I have hereto affixed my signature in the presence of two witnesses.

GEORGE W. GOMBER.
